Attorney

UNITED STATES PATENT OFFICE.

LEANDER L. DUNBAR, OF LINN GROVE, INDIANA.

CUSHION-FILLING MACHINE.

Application filed November 26, 1924. Serial No. 752,446.

To all whom it may concern:

Be it known that I, LEANDER L. DUNBAR, a citizen of the United States, residing at Linn Grove, in the county of Adams and State of Indiana, have invented certain new and useful Improvements in Cushion-Filling Machines, of which the following is a specification.

My said invention relates to a machine for filling cushions, pillows and analogous devices and it is an object of the same to provide means whereby the filling may be fed into a cushion or the like smoothly and expeditiously and in such a manner as to fill the same uniformly throughout its entire extent.

Referring to the accompanying drawings, which are made a part hereof and on which similar reference characters indicate similar parts—

Figure 1 is a perspective of my device,

Figure 2, a perspective of an attachment used with the machine;

Figure 3, a longitudinal vertical section of the machine; and

Figure 4, a transverse vertical section thereof.

In the drawings reference character 10 indicates a table supported in any desirable manner on the frame work which may comprise posts 11 and braces 12 and 13. The table may be attached directly to the posts but preferably is secured to cross bars 14 near the ends of the table and additional cross bars 15 are located between the cross bars 14 for purposes hereinafter described.

A ram 16 is slidably mounted on the table, the head of the ram being a little above the surface of the table as shown in Figure 3. The ram has a rearwardly extending stem 17 with ratchet teeth 18 on the upper side thereof, said stem extending through a guide 19' and through the end of a lever 19 pivoted at 20 on a cross-bar 13. The lever is provided at its upper end with a yoke 21 embracing the stem 17 and a pawl 22 is pivotally supported by the yoke. The pawl has a lateral extension 23 adapted to ride over a fixed lifter 24 by means of which the pawl is lifted out of engagement with the teeth on the stem 17, which teeth form a ratchet bar adapted to be operated by the pawl 22 for advancing the ram.

Means for operating the lever as illustrated in the present embodiment of the invention comprises a rod 25 pivoted at one end to the lever and pivotally connected at the other end to a strap 26 passing over a roller 27 carried by a bracket or brackets at the under side of one of the cross bars 15. At 60 its free end the strap is secured to a cross bar 28 of a treadle having side members 29 and a foot piece 30. The treadle is pivoted at 31 on braces 12. A spring 32 is attached at one end to the lower end of lever 19 and at the other end to a cross bar 28 of the treadle, said spring serving to return both the treadle and the lever to their normal positions by reason of its connection above the pivot 31 whereby the spring is stretched as the cross bar 28 and the lower end of lever 19 both move downward toward alinement with the pivot 31 as the treadle is actuated.

A pair of bars 33 are located above the top of the table said bars, being swingable crosswise of the table and being here shown as supported by pairs of uprights 34, each upright being secured to a brace 12 by means of a strip of sheet metal 35 which may take the form of a leaf spring tending to throw the bars 33 outward away from the center line of the table. Below the table each pair of bars is connected by a bowed strip of sheet metal 36 which strips are connected by a rod 37 about which a coiled spring 38 is positioned, the coiled spring being of such a length as to bear at its opposite ends against the respective strips 36 and serving to separate the bars 33 in a resilient manner. A pair of shafts 39 extend lengthwise of the table adjacent the center line, the shafts being arranged in parallelism to each other and journaled in supports 40 one of which is carried by a cross-bar 15 and the other is here shown as carried by the uppermost cross-bar 14. The respective uprights 34 are each connected to one of a series of pulleys 41 by a strap 42. As will be evident from the drawings each shaft carries a pulley 41 near each end. Another pulley 43 is mounted approximately at the middle of each shaft and these pulleys 43 are connected by a strap 44 in a manner to rotate the shafts in opposite senses.

At the front of the machine there is a

handle 45 carried by an extension on one of the shafts 39 and between the handle and the cross-bar 18 a ratchet 46 is secured to said extension. A pawl 47 is pivotally supported adjacent the ratchet on one of the posts 11.

The material 48, which is intended to form the stuffing of the cushion or other object is assembled in a sufficient quantity between a pair of filling containers comprising side members 49 and top and bottom members 50 and 51 respectively. The filling material may consist of any desirable material for the purpose and may have springs arranged therein in appropriate manner according to the position they are to assume in the finished article.

The containers are preferably made of sheet steel with their parts hinged together as shown in Figure 2 and when the filling 20 has been properly disposed on the overlapping bottom members 51 the other parts are brought into position as indicated whereupon the entire package is placed in position on the top of the table. A compressing 25 member consisting of a disk 52 located at the end of a freely slideable bent support 53 is then thrust down on the top members 50 to bring them into parallelism as in Figure 4, the filling material being compressed accordingly. It is to be understood that the 30 compression member as shown merely has its vertical leg arranged to slide up and down through the table top but this may be journaled in various ways and may be provided with means for moving it up and 35 down and for securing it in various positions.

The package being placed in the position indicated in Figure 4, the operator will now 40 turn the handle 45 to revolve the shafts 39 and throw the uprights 34 and their grippers 33 toward the center line of the table. These grippers press against the side pieces 45 49 to further compress the filling material until the containers shall have been so far compressed by the action of the lateral grippers and the upper compressor as to bring the filling material to a size adapted to enter the cushion. The pawl 47 will now hold the 50 grippers in position. The operator may then place his foot on the treadle 29 and depress it to force the bar forward and thus force the filling material out of the container into the cushion, the end of which has preferably 55 been placed over the forward end of the package formed by the two containers above described.

The arrangement of the treadle and co-acting parts is preferably such that the operator will have to move the treadle up and down several times to complete the operation of filling the cushion, the stroke of the pawl being such as to force the ram ahead several steps at a time but not to the full extent of its stroke. As seen in Figure 3 the

ram is elevated above the table sufficiently to clear the lower members 51 of the containers. Preferably the table top has a metal reinforcement 53' adjacent the yoke 21 to prevent needless wear. A pin 54 on the stem 17 limits the extreme forward position of the ram by striking against the rear side of the yoke.

It will be obvious to those skilled in the art that numerous changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. A cushion filling machine comprising a table, transversely movable means at one side of the table for compressing a mass of filling material, a rotatable element beneath said table, and a strap having one end connected with the transversely movable means and having its other end connected with said rotatable element whereby when the rotatable element is rotated the strap will be wound about the same and the transversely movable compressing means will be operated, substantially as set forth.

2. A cushion filling machine comprising a table, a transversely movable element at each side of the table for compressing a mass of filling material, a rotatable element beneath said table, a pair of straps each having one end secured to the rotatable element and having its other end connected to a transversely movable element and adapted to be wound about said rotatable element to operate the transversely movable compressing elements, substantially as set forth.

3. A cushion filling machine comprising a table, transversely movable means at one side of the table for compressing a mass of filling material, a rotatable element beneath said table, a strap having one end connected with the transversely movable means and having its other end connected with said rotatable element whereby when the rotatable element is rotated the strap will be wound about the same and the transversely movable compressing means will be operated, and a ratchet on said rotatable element for holding said transversely movable compressing means in advanced relation, substantially as set forth.

4. A cushion filling machine comprising a table, transversely movable means at one side of the table for compressing a mass of filling material, yieldable means for urging the transversely movable means toward the side of the table, a rotatable element beneath said table, and a strap having one end connected with the transversely movable means and having its other end connected with said rotat-

able element whereby when the rotatable element is rotated the strap will be wound about the same and the transversely movable compressing means will be operated, substantially as set forth.

5. A cushion filling machine comprising a table, a transversely movable element at each side of the table for compressing a mass of filling material, means normally tending to force the transversely movable elements away from each other, a rotatable element beneath said table, a pair of straps each having one end secured to the rotatable element and having its other end connected to a transversely movable element and adapted to be wound about said rotatable element to operate the transversely movable compressing elements, substantially as set forth.

6. A cushion filling machine comprising a table, transversely movable means at one side of the table for compressing a mass of filling material, a rotatable element beneath said table, a strap having one end connected with the transversely movable means and having its other end connected with said rotatable element whereby when the rotatable element is rotated the strap will be wound about the same and the transversely movable compressing means will be operated, and a ram for feeding the filling material into a cover, substantially as set forth.

7. A cushion filling machine comprising a table, transversely movable means at one side of the table for compressing a mass of filling material, a rotatable element beneath said table, a strap having one end connected with the transversely movable means and having its other end connected with said rotatable element whereby when the rotatable element is rotated the strap will be wound about the same and the transversely movable compressing means will be operated, a ram for feeding the filling material into a cover, and pawl and ratchet mechanism for advancing said ram, substantially as set forth.

8. A cushion filling machine comprising a table, transversely movable means at one side of the table for compressing a mass of filling material, a rotatable element beneath said table, a strap having one end connected with the transversely movable means and having its other end connected with said rotatable element whereby when the rotatable element is rotated the strap will be wound about the same and the transversely movable compressing means will be operated, a ram for feeding the filling material into a cover, pawl and ratchet mechanism for advancing said ram, and treadle mechanism for operating said pawl and ratchet mechanism, substantially as set forth.

9. A cushion filling machine comprising means for supporting a mass of filling material in operative relation to a cushion cover, a ram to force said material into said

cover, a rack bar secured to the ram, a lever pivoted adjacent thereto, a pawl on the lever engaging the rack bar, a treadle for operating the lever, and a spring connected to the treadle and the lever in a manner to return each of them after an operation of the treadle, substantially as set forth.

10. A cushion filling machine comprising means for supporting a mass of filling material in operative relation to a cushion cover, a ram to force said material into said cover, a ratchet bar secured to the ram, a lever pivoted adjacent thereto, a pawl on the lever engaging the ratchet bar, a treadle for operating the lever, a lifter on the table adjacent the ratchet bar for disengaging the pawl from the same, and a spring connected to the treadle and the lever in a manner to return them after operation of the treadle, substantially as set forth.

11. A cushion filling machine comprising means for supporting a mass of filling material in operative relation to a cushion cover, a ram to force said material into said cover, a ratchet bar secured to the ram, a lever pivoted adjacent thereto, a pawl on the lever engaging the ratchet bar, a treadle for operating the lever, a spring connected to the treadle and the lever in a manner to return each of them after operation of the treadle, and interengaging means on the lever and the ratchet bar for limiting the forward movement of the ram, substantially as set forth.

12. A cushion filling machine comprising a table, a transversely movable gripper at one side of the table for compressing a mass of filling material, a rotatable shaft beneath the table having a handle on one end, a ratchet wheel mounted on said shaft adjacent said handle, a gravity operated pawl engaging said ratchet wheel, and a strap having one end connected with said gripper and its other end connected with said shaft whereby when the pawl is rotated the strap will be wound about the same to operate the gripper and the pawl will engage the ratchet and hold said gripper in advanced position, substantially as set forth.

13. A cushion filling machine comprising a table, a cross-bar beneath said table adjacent each side thereof, spaced uprights secured by means of flexible connections to said cross-bars permitting each upright to swing in an arc with the upper end thereof disposed above the table, and opposed grippers mounted above the table on said uprights and adapted to be moved toward and from each other to compress the filling material, substantially as set forth.

14. A cushion filling machine comprising a table, a cross-bar beneath said table adjacent each side thereof, spaced uprights secured by means of flexible connections to said cross-bars permitting each upright to

swing in an arc with the upper end thereof disposed above the table, and opposed grippers mounted above the table on said uprights and adapted to be moved toward and from each other to compress the filling material said flexible connections tending normally to urge said uprights and the grippers

supported thereby apart, substantially as set forth.

In witness whereof I have hereunto set my ¹⁰ hand and seal at Linn Grove, Indiana, this twenty second day of November, A. D. nineteen hundred and twenty-four.

LEANDER L. DUNBAR. [L. S.]
